UNITED STATES PATENT OFFICE.

LEWIS H. BROOME, OF JERSEY CITY, NEW JERSEY.

DESIGN FOR A BOTTLE-STOPPER PLUG.

SPECIFICATION forming part of Design No. 31,233, dated July 18, 1899.

Application filed June 24, 1899. Serial No. 721,786. Term of patent 7 years.

To all whom it may concern:

Be it known that I, LEWIS H. BROOME, a citizen of the United States, residing at Jersey City, in the county of Hudson and State of New Jersey, have invented and produced a new and original Design for a Bottle-Stopper Plug, of which the following is a specification, reference being had to the accompanying drawings, forming part thereof, in which—

- Figure 1 is an elevation, Fig. 2 an inverted plan, and Fig. 3 a vertical section, illustrating my design.

As shown in the drawings, the bottle-stopper plug is round; and the leading or material feature of my design consists of the compound curved or ogee sides of the stopper-plug. The

top *a* is slightly convex and the sides at *b* straight, but downwardly converging. The sides at *c c* are compound curves or of ogee shape. The lower end *d* is convex, and the ²⁰ annular groove *e* is between the end *d* and the body of the stopper-plug, and the opening *f* through the body of the plug is approximately semicircular in configuration.

What I claim is—

The design for a bottle-stopper plug, substantially as shown and described.

Signed by me this 20th day of June, 1899.
L. H. BROOME.
